UNITED STATES PATENT OFFICE.

JOSEPH B. STRAUSS, OF CHICAGO, ILLINOIS.

RAILWAY-CAR.

1,390,396.

Specification of Letters Patent. Patented Sept. 13, 1921.

Application filed December 19, 1914. Serial No. 878,028.

To all whom it may concern:

Be it known that I, JOSEPH B. STRAUSS, a citizen of the United States, residing at Chicago, in the county of Cook and State of Illinois, have invented a certain new and useful Improvement in Railway-Cars, of which the following is a specification.

This invention relates to improvements in railway cars, and particularly elevated rail-
way cars where the rails for the cars are located above the cars, the cars being suspended from trucks running on said rails.

The invention is illustrated in the accompanying drawings, wherein,
15 Figure 1 is a diagrammatic view of one of the cars;

Fig. 2 is a side view of one end of a car embodying the invention;

Fig. 3 is a sectional view of the car taken 20 on line 3—3 of Fig. 2.

Fig. 4 is a side elevation of the truck and the parts of the car by means of which it is connected with the truck.

Like numerals refer to like parts through 25 the several figures.

Referring now to the drawings, I have shown a car-body 1 suspended from overhead. This car is provided at the top with a central beam 2 which is preferably made 30 in the form of a truss, and the car, is, as it were, built around this upper central truss. At intervals along the car body, and particularly at the points where it is suspended, I have provided stiffening frames. These 35 stiffening frames are preferably made of metal and consist of the side pieces 3, the top piece 4 and the spreader piece or frame 5. This stiffening frame is connected at the bottom to the floor 6 of the car, thereby forming 40 a rigid stiffening structure to take the strains while the car is in operation. The spreader-frame or part 5, holds the side pieces 3 apart, and the top piece 4 is connected with the upper central truss 2. Located between 45 the part 4 of the frame and the spreader frame 5, are the compression members 7. Connected with the stiffening frames are the connecting devices or straps, 8 which pass up above the central truss 2, and are connected 50 therewith through the hanger pieces 9, said connecting devices 8 being connected to the hanger pieces 9 which are in turn connected with the central truss 2. The connecting de-

vices 8 have separated ends and the spreading devices 5 extend between these separated 55 ends to take the transverse strains, see Fig. 3.

The hanger pieces 9 attached to the central truss 2, are pivotally connected at 10 with the supporting pieces 11 mounted on the trucks 12. This forms a free hanger connection by means of which the cars are connected with the trucks through the central truss 2.

There is a second safety connection between the car and the trucks consisting of 65 the chain or flexible connecting device 13, which passes through the roof of the car, and through the main central truss and engages a curved supporting or seating part 14 connected with said central truss. The ends 70 of this chain are connected with the trucks.

Under ordinary conditions the support or seating device 13 is without load and only receives its load in the event the pivotal connection becomes disarranged. 75

There is a safety yoke 15 also connected with the central truss 2 and it is located between the wheels of the truck, the ends thereof projecting beyond the rails 16, so that if, for any reason the car becomes disconnected from the truck, the safety yoke 80 will strike the rails and support the car.

It will be seen that there are three supporting connections between the car and the over-head structure, two of said supporting 85 connections being through the truck and the third being independent of the truck.

A hood 17 of any desired material, such for example, as sheet metal, is spread over the stiffening frames and hanger parts or 90 straps 8, so as to make a finishing structure. This also forms a compartment at the top of the car which furnishes storage room for air reservoirs, batteries and the like. The truck 12 carries the electric contact device 18, 95 which is in the form of a sliding shoe movably connected with the truck and which presses against the bottom of the contact rail 19. This contact rail is located above the truck so as to be out of the way and where 100 there can be no danger from it to passengers or others, and is provided with a hood or protecting device 20 to protect it from the elements.

The truck 12 has its ends 21 projecting 105 beyond the wheels 22, and associated with

one of these projecting ends is a pump or air compressor 23 operated by a motor shown in dotted lines, Fig. 4, for the car brakes, and with the other projecting end, a motor 24, this motor being the motor which operates the car. It will be seen that the pump and motor are at opposite ends of the truck and therefore act to balance each other.

I claim:

- 10 1. A car comprising a body portion, a stiffening frame connected with said body portion, said stiffening frame having side pieces and a cross piece at the top connecting said side pieces, and a central beam extending longitudinally of the car body substantially throughout the length of the car and connected with said stiffening frame.
- 15 2. A car comprising a body portion, a stiffening frame connected with said body portion, said stiffening frame having side pieces and a cross piece at the top connecting said side pieces, and a central beam extending longitudinally of the car body substantially throughout the length of the car and connected with said stiffening frame, a truck above said body portion and a supporting connection between said truck and said stiffening frame.
- 20 3. A car comprising a body portion, a stiffening frame connected with said body portion, said stiffening frame having side pieces and a cross piece at the top connecting said side pieces, and a central beam extending longitudinally of the car body substantially throughout the length of the car and connected with said stiffening frame, and a truck above said body portion and a supporting connection between said truck and said longitudinal beam.
- 25 4. A car comprising a body portion, a stiffening frame connected with said body portion, said stiffening frame having side pieces and a cross piece at the top connecting said side pieces and a central beam extending longitudinally of the car body and connected with said stiffening frame, a truck above said body portion and two supporting connections between said truck and said body portion, one of said connections being an operative connection in use when the car is in operation, and the other connection being a safety connection adapted to be brought into use when the first connection becomes disarranged.
- 30 5. A car comprising a body portion, a stiffening frame connected with said body portion, said stiffening frame having side pieces and a cross piece at the top connecting said side pieces, and a central beam extending longitudinally of the car body and connected with said stiffening frame, a truck above said body portion and adapted to run upon a fixed support, a connection between said body portion and said truck, and a safety supporting device independent of the truck

and adapted to support said body portion on the fixed support near the connection to the truck face.

6. A car comprising a body portion, a truck located above said body portion and adapted to be supported upon a fixed support, three connecting devices arranged to successively support the body portion on said fixed support under predetermined conditions, two of said supporting devices acting through the truck, one adapted to act when the other fails, the third supporting device acting independently of the truck when the first two supporting devices fail.

7. A car comprising a body portion, a stiffening frame therefor comprising side pieces and a cross connecting piece at the top, and a spreading frame between the side pieces.

8. A car comprising a body portion, two separated stiffening devices connected with said body portion, hanger devices connected with said stiffening devices and adapted to be connected with the support for the car, and a metal hood connecting said hanger devices and extending longitudinally along the car so as to form a storage receptacle beneath said hangers.

9. A car comprising a body portion, hanger devices located at different points along the body portion for connecting it with its supporting device, each hanger device having connecting pieces connected therewith, the said connecting pieces having separated ends and spreading frames connected with said connecting pieces and extending between said separated ends to take the transverse strains.

10. A car comprising a body portion, hanger straps connected with said body portion at different points along its length and spreading frames extending across the car between the lower ends of said straps adapted to keep said ends apart.

11. A car comprising a body portion, hanger straps connected with said body portion at different points along its length and spreading frames extending across the car between the lower ends of said straps adapted to keep said ends apart, and a longitudinal beam extending along the car, said beam located between said hanger straps and said spreading frames.

12. A car comprising a truck, a frame for said truck, wheels connected with said frame at each end thereof, the ends of the frame projecting beyond the wheels, a motor connected with one end of the frame, a pump connected with the other end of the frame whereby the pump and motor balance each other.

13. A car comprising a body portion, a beam at the top of the car extending longitudinally therealong, a stiffening frame having side pieces connected with said car, a cross piece extending across the car and a

hanger connecting the side pieces extending over said beam, the beam located between said hanger and said cross piece.

14. A car comprising a body portion, a stiffening frame connected with said body portion, said stiffening frame having side pieces and a cross piece at the top connecting said side pieces, a central beam extending substantially throughout the length

of the car and connecting devices between 10 said central beam and said stiffening frame.

In testimony whereof, I affix my signature in the presence of two witnesses this 14th day of December, 1914.

JOSEPH B. STRAUSS.
